UNITED STATES PATENT OFFICE.

RUDOLPH W. E. CHRISTENSEN, OF NEW BRITAIN, CONNECTICUT, ASSIGNOR
TO THE RUSSELL & ERWIN MANUFACTURING COMPANY, OF SAME PLACE.

DESIGN FOR A KNOB AND LOCK ESCUTCHEON.

SPECIFICATION forming part of Design No. 21,706, dated July 12, 1892.

Application filed May 31, 1892. Serial No. 435,079. Term of patent 14 years.

To all whom it may concern:

Be it known that I, RUDOLPH W. E. CHRISTENSEN, a citizen of the United States, residing at New Britain, in the county of Hartford and 5 State of Connecticut, have invented and produced a new and original Design for a Knob and Lock Escutcheon, of which the following is a specification, reference being had to the accompanying drawing, showing the same.

10 The single figure in the drawing is a front elevation of an escutcheon, showing my design.

The leading feature of my design consists of a series of raised ornaments in the form of 15 intersecting scrolls, the same being of a rounded form in imitation of ornamental wire-work placed over a suitable ground.

A designates a rosette around the knob-escutcheon, said rosette consisting principally 20 of leaflets tangentially arranged. Surround-

ing the keyhole-escutcheons 1 and 2 is a rounding bead 3, extending up and down in straight lines on either side and squarely across the bottom, as shown. From the upper ends of these beads 3 3 the rounded wire-like beads 25 extend both up and down in the form of various branching scrolls 4, all in imitation of wire-work and interspersed with occasional leaflets 5 and bunches of conventional fruit 6, all being on a suitable ground. I also form ornamental transverse bars 7 at the upper and lower ends.

What I claim is—

The design for a knob and lock escutcheon, as herein shown and described.

RUDOLPH W. E. CHRISTENSEN.
